CLAIM

We claim the ornamental design for an electronic tracking device, as shown and described.

DESCRIPTION

FIG. 1 is a front perspective view of an electronic tracking device showing our new design.

FIG. 2 is a rear perspective view of the electronic tracking device in FIG. 1.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a front perspective view of another embodiment of an electronic tracking device showing our new design, where the radial lines in FIG. 9 indicate illumination of the circular region from which the radial lines emanate.

FIG. 10 is a rear perspective view of the electronic tracking device in FIG. 9.

FIG. 11 is a front view thereof, where the radial lines in FIG. 11 indicate illumination of the circular region from which the radial lines emanate.

FIG. 12 is a rear view thereof.

FIG. 13 is a right side view thereof.

FIG. 14 is a left side view thereof.

FIG. 15 is a top view thereof; and,

FIG. 16 is a bottom view thereof.

The line shadings in the figures are included for the purpose of illustrating contour and are not intended to be illustrative of texture or gloss. None of the broken lines form a part of the claimed design.
